UNITED STATES PATENT OFFICE.

CLARK S. HUTCHINSON, OF BURLINGTON, NEW JERSEY.

IMPROVEMENT IN TOBACCO-PIPES.

Specification forming part of Letters Patent No. 41,778, dated March 1, 1864.

To all whom it may concern:

Be it known that I, C. S. HUTCHINSON, of Burlington, Burlington county, New Jersey, have invented certain Improvements in Tobacco-Pipes; and I hereby declare the following to be a full, clear, and exact description of the same, reference being had to the accompanying drawings, and to the letters of reference marked thereon.

This invention consists in the peculiar arrangement of a sponge in relation to the bowl of the pipe, a case below the same, and an opening leading to the stem, whereby the smoke shall be cooled and deprived of its nicotine and the water from the sponge prevented from flowing into the stem or coming in contact with the tobacco, as hereinafter described.

The invention also consists in a combination of the sponge with a rod and perforated plates, in a manner and for a purpose fully specified hereinafter.

In order to enable others skilled in the art to make and use my invention, I will now proceed to describe its construction and operation.

On reference to the accompanying drawings, which form a part of this specification, Figure 1 is an exterior view of my improved tobacco-pipe; Fig. 2, is vertical section, and Fig. 3 a transverse section on the line 1 2, Fig. 2.

Similar letters refer to similar parts throughout the several views.

A is a hollow cylindrical case, closed at the bottom and having an inclined tube, B, communicating with the interior of the case through the opening x. In the top of the case fits the lower end of a cup or bowl, C, similar in form to the bowls of ordinary tobacco-pipes, and communicating with the interior of the case A through an opening, y.

Into the end of the tube B fits the lower end of a tube or stem, D, to which is attached the ordinary mouth-piece, E.

To the vertical rod f, which is bent at the upper end so as to form a handle, e, are secured the perforated, metal plates e and e', adapted to fit snugly, but so as to move freely in the inside of the case, and between the two plates, and surrounding the rod f, is a sponge, G. The lower end of the rod f extends below the plate e' to a sufficient extent to maintain the latter above the opening x, thus forming below the plate e' a chamber, G', for a purpose described hereinafter.

When the pipe is to be used, the bowl is removed, the rod f, with its plates and sponge withdrawn by means of the handle e, and the sponge saturated with water, after which it is again inserted in the case and the bowl replaced and filled with tobacco. As the smoke is drawn from the burning tobacco into the stem D, and thence to the mouth, it must pass downward through the opening y and the perforations in the plate e, through the interstices of the saturated sponge, the perforations of the plate e', and the opening x. As the smoke passes through the sponge, the water therein not only cools the smoke, but also absorbs the noxious nicotine.

It will be seen that by placing the opening x below the sponge, and above the bottom of the case any water which may be drawn from the sponge, instead of entering the stem D, as would be the case in ordinary pipes, will flow into the chamber beneath the plate e'; and in case the position of the pipe should at any time be wholly or partially reversed, the water will flow through the perforated plate e', and be again absorbed by the sponge without coming in contact with the tobacco or flowing into the stem. When the water in the sponge becomes foul from the quantity of nicotine absorbed, the bowl may be removed and the sponge withdrawn, as before, and detached from the rod f by removing the plate e'. A new sponge may then be substituted for the old one, or the latter may be washed and replaced.

In place of the detachable bowl C, the sides of the case A may be extended to a sufficient height above the plate e to form a receptacle for the tobacco. The shape of the pipe may be altered without departing from the main features of my invention, and other materials or substances may be used in place of the sponge.

I claim—

1. The sponge G, or its equivalent, adapted to the case A, and arranged in respect to the opening x, and the bowl C, or its equivalent, substantially as and for the purpose set forth.
2. The combination of the sponge G with the rod f and plates e, as set forth, for the purpose specified.

In testimony whereof I have signed my name to this specification in the presence of two subscribing witnesses.

Witnesses: C. S. HUTCHINSON.
